UNITED STATES PATENT OFFICE.

WALTER F. KEMBALL, OF WESTFIELD, NEW JERSEY, AND HARRY M. RUGG, OF NEW YORK, N. Y., ASSIGNEES TO VACUUM OIL COMPANY, OF NEW YORK, N. Y., A CORPORATION OF NEW YORK.

DISPLAY CABINET.

Application filed May 11, 1927. Serial No. 190,577.

The present invention relates to display cabinets and an object of the invention is to provide a display cabinet constructed in a strong and durable manner to withstand weather conditions. A further object of the invention is to provide a display cabinet with doors on opposite sides of shelves so that the contents of the shelves may be reached from either of two sides of the cabinet. Another object of the invention is to provide a cabinet having a door which may be swung so as to lie in parallel relation to one of the sides of the cabinet when in open position in order to display signs on the inner face of the door.

To these and other ends, the invention consists of certain parts and combinations of parts, all of which will be hereinafter described: the novel features being pointed out in the appended claim.

20 In the drawings:

Fig. 1 is a perspective view of a cabinet constructed in accordance with this invention;

Fig. 2 is an enlarged fragmentary section adjacent one of the joints between a side wall and the top;

Fig. 3 is a fragmentary perspective view of one of the angle irons showing the two projections one for holding one of the doors closed and the other for holding the other door open;

Fig. 4 is a fragmentary section of the lower portion of the cabinet;

Fig. 5 is a bottom view of the top of the cabinet; and

35 Figs. 6 and 7 are two vertical sections through the cabinet one at right angles to the other.

The illustrated embodiment of the cabinet comprises four angle iron corner pieces or uprights 1. Two side plates 2 are each spot welded or otherwise secured to the inner faces of a flange on each of two of the corner posts 1 so as to provide two opposite walls for the cabinet and these two sides are in turn connected at their upper ends by horizontal connecting pieces 3. The upper connecting pieces 3 are secured to the angle iron pieces 1 by angle tie pieces 5 bolted at 4 to the inner faces of the angle iron pieces 1 and the cross pieces 3. Inwardly turned flanges 6 are provided on the upper edges of the side plates 2 and inwardly turned flanges 7 are provided along the upper edges of the cross pieces 3. These flanges 6 and 7 serve for securing a top to the cabinet.

50 The top in this embodiment of the inven-

tion is of frusto-pyramidal formation and comprises a top plate 8 spot welded or otherwise secured to four side pieces 9. These side pieces decline or flare outwardly and downwardly from the piece 8 and have downwardly presented flanges 10 along their opposite edges, the flanges on adjacent sides being arranged in abutting relation and being bolted together at 11. Each of the walls 9 has at its lower edge a vertically arranged portion 12 and from the lower edge of this vertically arranged portion the portion 13 extends horizontally in an inward direction, there being arranged between the vertical portion 12 and a horizontal portion 13 a depending head 14. The portions 13 on the four walls provide a continuous inwardly extending flange on the top, while the flanges 6 and 7 on the main portion of the cabinet provide a continuous inwardly extending flange on the top portion of the cabinet frame. These two continuous flanges are bolted together by bolts 15. The top of the cabinet has a greater horizontal cross section at its base than the top portion of the cabinet frame so that when the top of the cabinet is bolted to the frame, the top projects beyond the cabinet frame and acts to shed water away from the joint with the cabinet frame. This is assisted by the bead 14 which tends to collect all the water at the perimeter of the top of the cabinet.

The bottom of the cabinet is formed by a rectangular sheet metal piece 16 provided at two sides with depending flanges 17 having inwardly turned edges 18. The other two sides of the bottom piece 16 are provided with shorter flanges 19. The interior faces of the side plates 2 are provided near their lower ends with strips 20 which are secured to the side walls 2 adjacent the lower edges of such strips, the upper edges being spaced from the side walls to provide grooves between the strips and the side walls in which the flanges 19 on the two opposite sides of the bottom 16 are received. Legs or supports 21 have portions 22 abutting the under side of the bottom and are shaped to fit in the corners of the cabinet frame, bolts 23 pass through the legs or supports, the flanges 17 and the angle iron pieces 1, and serve to hold the legs or supports as well as the bottom member 16 in effective connection. The supports have openings extending therethrough and the bottom piece 16 has openings. Through the openings in both parts extend tie bolts 24 which have their lower ends an-

chored in a concrete base 25 so as to firmly hold the cabinet to a base. The nuts 26 on the upper ends of these bolts are located within the cabinet so that the cabinet can be removed from the bolts only by opening the cabinet. At the same time the bolts 24 are so positioned in reference to the legs of the support that they are substantially invisible.

The cabinet is provided with removable shelves 27 in the form of sheet metal plates with downwardly turned flanges 28 on all four sides. The supports for the shelves are, in this instance, in the form of strips having portions 29 welded or otherwise secured to the sides 2 and portions 30 spaced from the sides to provide grooves in which two of the flanges 28 on opposite sides of the shelves 27 may be received. These shelves are also provided adjacent opposite side edges with parallel angle iron pieces 31 each of which extends between two of the angle iron corner pieces and serves as a guide for trays or other articles which may be introduced into the cabinet through the two openings provided in the opposite sides of the cabinet. These guides prevent the trays or packages from engaging with the angle iron corner pieces when being moved into the cabinet or from the same from either side or door opening of the cabinet.

The doors 32 each extends between two of the angle irons 1 and also between the top piece 3 and the bottom wall 4, each door having a continuous flange 33 projected from the inner face thereof to reinforce the door and fit within its door opening. The hinges 34 of each door have their pintles at the corner of the angle iron corner posts. The purpose of this arrangement is to permit the door either to close a door opening or to lie flat against a panel or side connecting the two angle iron corner pieces, thus practically covering a closed side of a cabinet. The purpose of this is to enable the signs 35 on the inner face of the door to be properly exposed at the side of the cabinet when the latter is open. With the end in view of holding the doors 32 in closed and also in open position each door has, in this instance, a rigid projection 36 at its free or swinging edge provided with an opening 37 in which is adapted to be received a projection 38 on an angle iron upright 1 to

hold the door in closed position or a projection 39 on another upright 1 to hold the door in open position. Each of these projections 38 and 39 has an opening 40 through which a taper pin, padlock or other device may be passed to form a stop for the movement of the door. It will be noted that two diametrically opposite uprights have the doors 32 hinged thereto, while the other two diametrically opposite uprights are each provided with the two projections 38 and 39, one for engagement by one of the doors when in closed position and the other for engagement by the other of the doors when in opened position.

A globe 41 may surmount the top plate 8 for enclosing an electric bulb to which electrical conductors 42 may lead through an opening 43 in a top plate. The conductor may lead from a ground tube 44 extending through the concrete base 25.

From the foregoing it will be noted that there has been provided a cabinet especially designed for the outdoor display and storage of merchandise. In this instance, it is particularly designed for the display and storage of lubricating oil in small containers. The merchandise may be reached through either of the two sides of the cabinet and the doors to the cabinet are so mounted that when in open position they act as display signs at the closed sides of the cabinet. The cabinet has been constructed to provide a strong and durable structure adapted to withstand weather conditions.

What we claim as our invention and desire to secure by Letters Patent is:

A display cabinet comprising a cabinet frame having door openings on opposite walls, shelves supported by two other opposite side walls and extending from one open side to the other and accessible at both openings, and doors for closing said openings hinged at two diametrically opposite corners of the frame so that they may be swung in parallel relation to and against the other two walls of the cabinet when in extreme open positions so as to permit the inner faces of the doors to act as signs.
